MATRIX RETAINER

Benjamin F. Tofflemire, La Fayette, Calif.

Application June 18, 1946, Serial No. 677,577

10 Claims. (Cl. 32—63)

1

An object of my invention is to provide a matrix retainer that is especially adapted to hold an individually formed dental matrix band about a tooth, the matrix being made by the matrix band former and cutter shown in my copending application, Serial No. 674,354, filed June 4, 1946. In the copending case I disclose and claim a matrix band former and cutter that will cut a matrix band of the desired length and will diagonally fold the band substantially at the mid-point so that a subsequent bringing of the ends of the band into parallel relation will cause the portion with the diagonal fold to form a conical-shaped matrix that will conform to the tooth contour.

The matrix retainer permits an operator to easily and quickly adapt the matrix band about the prepared tooth cavity or cavities in such a manner that the natural contours of the tooth will be restored. The original tooth form can be preserved and the normal mouth hygiene maintained. The matrix retainer may also be quickly, easily and safely removed from the freshly packed restoration without prejudice to the contact point or points and without distortion of the marginal ridges.

A further object of my invention is to provide a matrix retainer that is controlled by a single control spindle, the operating end of which extends outside the oral cavity where the operator can have a clear field of vision and can manipulate the device without the necessity of reaching into the mouth to do so. The matrix retainer is simple in construction and can be used on any tooth in the upper or lower arch.

Other objects and advantages will appear in the following specification, and the novel features of the device will be particularly pointed out in the appended claims.

My invention is illustrated in the accompanying drawings forming a part of this application, in which:

Figure 1 is a top plan view of the matrix retainer on a greatly enlarged scale;

Figure 2 is a view of the clamping spindle;

Figure 3 is a side elevation of Figure 1, portions being shown in section;

Figure 4 is a side elevation of the spindle-receiving sleeve;

Figure 5 is an isometric view of the matrix retainer frame;

Figure 6 is an isometric view of the matrix band-gripping block;

Figure 7 is an isometric view of the matrix retainer applied to the ends of a matrix band that encircles a tooth;

2

Figure 8 is a side elevation of the conical matrix encircling the tooth;

Figure 9 is an isometric view of the conical matrix ready to receive a tooth;

Figure 10 is a plan view of a diagonally folded matrix band from which the conical matrix is formed;

Figure 11 is an isometric view of a modified form of matrix retainer;

Figure 12 is an isometric view of a modified form of band-gripping block used in the matrix retainer of Figure 11;

Figure 13 is an isometric view of the matrix retainer frame shown in Figure 11;

Figure 14 is a top plan view of the modified form;

Figure 15 is a side elevation of Figure 14; and

Figure 16 is an isometric view of the removable matrix band receiving head that is used in the modified form.

While I have shown only the preferred form of my invention, it should be understood that various changes or modifications may be made within the scope of the appended claims without departing from the spirit and scope of the invention.

In carrying out my invention, I provide a matrix retainer having a frame A of the shape shown in Figure 5. The frame has a longitudinally extending guideway 1 for a clamping block 30 B shown in Figure 6. The side 2 of the frame has a slot 3 for slidably receiving a pin 4, carried by the block. The frame has a head 5 that has a diagonally-extending slot 6 that communicates at one end with the guideway 1. The other end of the slot 6 communicates with a transversely extending slot 7 which in turn is bisected by a short longitudinally-extending slot 8 that communicated therewith. The slot 7 intersects the slots 6 and 8 at the juncture of the latter two with each other.

The clamping block B is slidably mounted in the guideway 1 and the pin 4 rides in the slot 3 to prevent the removal of the block from the frame. The block has a diagonally extending slot 5 that extends substantially through the block excepting for a web base portion 10, see Figure 6. In Figure 1 it will be apparent that the side 11 of the block is cut away at 12 to provide the necessary space to receive the two thicknesses of the matrix band material C. The portion of the block 5 disposed between the slot 9 and the rear wall 13 has a longitudinally extending threaded bore 14 therein.

A spindle indicated generally at D, see Figure 2, has a threaded portion 15 that is received in the

bore 14, and the spindle has a conical end 16 with a surface that parallels the wall 9a of the slot 9. The spindle may be rotated in the bore 14 to cause the conical head 16 to clamp the ends 17 of the matrix band against the wall 9a for securing the ends rigidly to the block. A movement of the block along the guideway 1 will now move the band ends therewith.

The means for moving the spindle D after it has clamped the band ends 17 to the block comprises a sleeve E that is shown in elevation in Figure 4. The sleeve has a spindle receiving bore 18, a portion of which is threaded at 18a for receiving the spindle threaded portion 15. The sleeve has a reduced shank portion 19 rotatably receivable in a bore 20 provided in the end 21 of the frame A. An annular shoulder 22 rotatably bears against the end wall 23 of the frame. The frame carries a set screw 24 that is slidably received in an annular groove 25 formed in the shank 19 so as to prevent the withdrawal of the sleeve E while permitting its rotation in the frame. The spindle has a handle 26 that projects beyond the end of the sleeve E.

Before describing the operation of the tool, it is best to set forth briefly the form of the matrix C that is made from dental matrix band with the instrument disclosed and claimed in my copending case above referred to. The folded band is illustrated in Figure 10, and it comprises the fold 27 and the ends 17. The ends of the band are brought together as in Figure 9 and the fold 27 causes the matrix C to be conical in shape. The matrix encloses a tooth F in Figure 8 with the band ends 17 being shown extending from the matrix at the center thereof. The band ends 17 are slipped edge-wise into the slots 7, 6 and 9 before the conical matrix C is slipped over the tooth. Adjustment of either end 17 can be made so that the fold 27 will be on the lingual aspect of the tooth.

Referring to Figure 7, I show the tooth F as being the right lower first molar and situated between the second bicuspid G and the second molar H. The matrix C received the molar F and the ends 17 extend from the buccal side of the tooth. The ends have been previously inserted into the slots 7 and 6 of the frame A and the slot 9 of the block B. The handle 26 is rotated for causing the spindle conical end 16 to clamp the ends 17 to the block. The sleeve E is now rotated for causing the spindle to move the block along the guideway 1 for tightening the ends 17 and pulling the conical matrix C snugly about the tooth F. The matrix band material will slide through the slots 6 and 7 during this movement. The slots 6, 7 and 9 place no limitation on the width of the matrix band material that can be used because the slots are entirely open along one side. Moreover, the retainer may be inverted when used if desired.

The sleeve E and handle 26 project beyond the patient's mouth so that the operator may manipulate either without putting his fingers into the mouth. A clear view of the tooth is possible with this arrangement and ease of manipulation is assured. The filling in the tooth is indicated at 28. The fold 27 of the matrix is placed on the lingual aspect of the tooth and the matrix extends down to the gingival surface 29. A matrix band of the desired height can be used by the same matrix retainer. The filling 28 is indicated as extending from the mesial aspect of the tooth, across the occlusal surface, and down along the distal surface. The conical shape of the matrix

assures that the filling will restore the natural contours of the tooth.

There will be no excessive gingival overhanging of metal masses. The matrix retainer may be tightened to insure peripheral adaption and the grip of the matrix at the gingival margin permits thorough and adequate condensation of the filling material without any of the filling material being forced out beneath the gingival peripheral border.

10 The matrix band may be quickly, easily and safely removed from the freshly packed restoration without prejudice to the contact point or points and without distortion of the marginal ridges or the dislodging, breaking off or the removal of the newly placed filling material.

15 To free the matrix retainer from the band, the handle 26 is turned while holding the sleeve E from rotating. This backs the conical end 16 from the band and the matrix retainer can now be freed from the band by sliding it transversely with respect to the band width in a direction to move the band ends out from the open sides of the slots, after which the band may be freed from the tooth. The manipulation of the handle 26 and the holding of the sleeve E is accomplished outside the oral cavity. This is of the greatest possible convenience and comfort to the patient.

20 The matrix retainer is applicable to hold bands that enclose any tooth in the arch. The band material may be received in either side of the slot 7 as shown in Figure 1, or the band material may be received through the end slot 8, this depending upon the position that best fits the need of the operator. The inclined plane of the slot 9 cooperates with the spindle D so that a tightening of the spindle will tend to move the band ends into the slot and toward the base 10. A loosening of the spindle will tend to move the band ends out of the slot.

25 The "inverted-cone" principle of the specially formed matrix band actually results in a more positive gingival grip of the matrix about the tooth as the filling material is condensed into the cavity. The resulting "occlusal-flare" permits the operator to build the filling out as snugly as he wishes to condense the filling material against the adjoining tooth. The device lends itself admirably to the mechanical separation of the teeth where this may be necessary. The matrix band 30 may be removed from the tooth in one piece after the matrix retainer has been freed therefrom. In case of unusually tight contact points, the band may be severed at the narrowed lingual fold and the mesial and distal halves gently rotated lingually and toward the gingival floor, thereby actually tending to seat the filling more firmly during the band removal, instead of the occlusal withdrawal plane, necessarily employed by other types of matrix band retainers.

35 In placing the band ends 17 in the matrix retainer preparatory to moving the conical-shaped matrix C over the tooth, it is easier to set the band ends in sidewise in the slots rather than thread them through a slot which is required by other matrix retainers.

The size of the conical matrix C can also be controlled and the fold 27 can be kept on the lingual aspect of the tooth during the adjustment because either band end 17 can be moved with respect to the other.

40 In the modified form of the matrix retainer shown in Figures 11 to 16, inclusive, the operation of the parts are substantially the same as that shown in Figure 7. The device is changed slightly in the block that clamps the matrix band ends 45 and the block moving means. Furthermore, the

head for the frame is made removable and this permits the block to be moved into the frame more readily.

The frame A' has an open end as shown at 30 in Figure 13. The open end communicates with a guideway 1a in which a clamping block B' is slidably disposed. The particular shape of the clamping block B' is disclosed in Figure 12 and it has a diagonally extending slot 9b that terminates at the center of the block end 31 rather than at the side as shown in Figure 6. The block still has the web base 10a and in place of the pin 4 the block has opposed parallel flanges 32 projecting from opposite sides of the block and adapted to ride on the top and bottom edges of the frame A'. A cross section through the block might be likened to that of a small I-beam with the flanges 32 constituting the top and bottom portions.

The block is moved into the guideway 1a after which the removable head J is secured in place. The head is shown in Figure 16 and takes the place of the integral head 5 in the frame shown in Figure 5. The removable head has a base portion 33 with upwardly extending and parallelly arranged sides 34 that are received within the open end of the guideway 1a. The sides 34 have threaded openings 35 that register with counter-sunk openings 36 provided in the free ends of the frame A'. Set screws 37 or other suitable fastening means are inserted in the openings 36 and are threaded into the openings 35 for securing the head J to the frame.

The base 33 of the removable head extends below the frame A' as shown in Figure 15 and the base supports fingers 38 that are spaced from the sides 34 to provide lateral guide slots 39 and 40 and are spaced from each other to provide a central guide slot 41. The slot 41 communicates with the slots 39 and 40 and also communicates with a slot 42 that is formed between the sides 34. Before describing how the slots are adapted to receive the matrix band ends, I will set forth the construction for clamping the band ends to the block B' and for moving the block along the guideway 1a.

The closed end of the frame A' has a yoke 43 which is integral with the end and which has its slotted portion spaced from the end and extending parallel therewith. A sleeve E' has an annular groove 44 placed near one end to form an integral collar 45. The collar is received in the space between the yoke 43 and the closed end of the frame A' while the two sides 46 of the yoke rotatably receive the grooved portion 44 of the sleeve. It is possible to rotate the sleeve with respect to the frame, but the collar 45 prevents longitudinal movement thereof. The sleeve has a threaded bore 18b for receiving the spindle D'.

The closed end of the frame has an opening 47 through which the spindle D' extends. The spindle has its threaded portion 15a not only received in the threaded bore 18b of the sleeve, but also received in a threaded bore 14a provided in the block B', see Figure 14. The tapered end 16a clamps the matrix band ends 17 against the inclined wall 9c of the slot 9b. The band ends are clamped to the block B' when the handle 26a of the spindle is rotated for moving the tapered end 16a against the band ends. The two ends of the band can now be moved by the block B' and this is accomplished by rotating the sleeve E' in the desired direction. The spindle slides freely through the opening 47 during this movement.

The band ends 17 can be fed into the slots in

the head J and in the block B' in the same side-wise movement as accomplished with the form shown in Figure 1. The conical-shaped matrix C shown in Figure 14 has its ends 17 passing through the slot 39 and then through the slots 42 and 9b. The fold 27 in the matrix band will be on the lingual side of the tooth F. It is possible to have the conical matrix band C extend from the central slot 41 or from either side slot 39 or 40.

Since the operation of this form of the device is the same as that already explained for the form shown in Figure 1, further description of the operation need not be given. The slot 9b in the block E' has one end centered with respect to the slot 42. The slot 42 extends parallel with the longitudinal axis of the frame rather than at an angle as does the slot 6 in Figure 1. The two ends of the band 17 can be slipped into place in the slots more readily with this arrangement.

I claim:

1. A matrix band retainer comprising a frame, a matrix band end gripping block slidable along the frame, said frame having a slotted head for permitting the ends of a band forming a conical tooth-receiving matrix to be threaded therethrough to permit the matrix to extend from the end of the head or from either side thereof, means for securing the band ends to the block, and means for moving the block along the frame for contracting the matrix about the tooth.

2. A matrix band retainer comprising a frame, a matrix band end gripping block slidable along the frame, said frame having a slotted head for permitting the ends of a band forming a conical tooth-receiving matrix to be threaded therethrough to permit the matrix to extend from the end of the head or from either side thereof, means for securing the band ends to the block, and means for moving the block along the frame for contracting the matrix about the tooth, said band securing means including a manually actuated screw that is received in threaded bores provided in the block and in the frame end disposed opposite to the head, the block having a band end receiving slot with a wall, the end of the screw being received in the threaded block bore and adapted to clamp the band ends against the block slot wall, said block moving means comprising a threaded sleeve mounted on the screw, and means rotatably connecting the sleeve to the frame and preventing longitudinal movement of the sleeve with respect to the frame.

3. A matrix band retainer comprising an elongated frame having slots at one end for receiving the ends of a matrix band end gripping block slidable along the frame and having a slot for receiving the band ends, the slots in the frame and block being open along one side for permitting the band ends to be fed into the slots and removed therefrom sidewise, band end gripping means carried by the block and projecting through the frame end disposed opposite to the slotted frame end, said means projecting clear of the mouth and being manipulated from a point exterior to the mouth, and means cooperating with said last-named means and manipulated from a point exterior of the mouth for moving the block along the frame for tightening the looped portion of the matrix band around a tooth or for loosening the loop from the tooth.

4. In a matrix retainer, a frame having an elongated guideway, a band-clamping block slidable along the guideway and having a band-receiving slot therein, a head removably secured to

the frame at one end and having slots therein for receiving the band ends, the slots in the block and head opening out onto the same side of the frame for permitting the band ends to be fed sidewise into the desired slots at the same time, and means operable from a point beyond the other end of the frame for clamping the band ends to the block, said means including means also operable from a point beyond the said frame end for moving the block in the desired direction along the guideway.

5. In a matrix retainer, a band-clamping block having an inclined slot therein opening out onto one exposed side of the block, said block having a threaded bore extending from one end of the block and communicating with the slot substantially midway between its sides, and a threaded shank received in the bore and having an end adapted to clamp the band ends received in the slot, against one of the slot walls, whereby the band ends will be clamped to the block.

6. In a matrix retainer, a band-clamping block having an inclined slot therein opening out onto one exposed side of the block, said block having a threaded bore extending from one end of the block and communicating with the slot substantially midway between its sides, and a threaded shank received in the bore and having an end adapted to clamp the band ends received in the slot, against one of the slot walls, whereby the band ends will be clamped to the block, a frame for slidably supporting the block and means for moving the shank for advancing the block in the desired direction along the frame.

7. In a matrix retainer, a band-clamping block having an inclined slot therein opening out onto one exposed side of the block, said block having a threaded bore extending from one end of the block and communicating with the slot substantially midway between its sides, and a threaded shank received in the bore and having an end adapted to clamp the band ends received in the slot, against one of the slot walls, whereby the band ends will be clamped to the block, a frame for slidably supporting the block and means for moving the shank for advancing the block in the desired direction along the frame, the frame having an opening in one end for slidably and rotatably receiving the shank, said shank moving means including a threaded sleeve mounted on the shank and having one end rotatably connected to the frame so that the sleeve will project beyond the frame, the end of the shank projecting beyond the free end of the sleeve being provided with a handle, both the free end of the sleeve and the handle being adapted to project exterior of the mouth when the matrix retainer clamps a band to a tooth so that both may be manually actuated at points in front of the mouth.

8. In a matrix retainer, a frame, a matrix band end clamping block slidably carried by the frame, said frame having a head at one end with a central band-receiving slot extending throughout the length of the head and two laterally-extending band-receiving slots communicating with the first slot and extending to opposite sides of

the frame, the central slot being adapted to receive the band ends of a matrix forming band whether the band ends are fed in from either lateral slot or entirely received in the length of the central slot, and means carried by the clamping block for clamping the band end portions that extend beyond the inner end of the central slot, said block being movable for drawing in the band ends for tightening the matrix about a tooth.

9. In a matrix retainer, a frame, a matrix band end clamping block slidably carried by the frame, said frame having a head at one end with a central band-frame having a head at one end with a central band-receiving slot extending throughout the length of the head and two laterally-extending band-receiving slots communicating with the first slot and extending to opposite sides of the frame, the central slot being adapted to receive the band ends of a matrix forming band whether the band ends are fed in from either lateral slot or entirely received in the length of the central slot, and means carried by the clamping block for clamping the band end portions that extend beyond the inner end of the central slot, said block being movable for drawing in the band ends for tightening the matrix about a tooth, said band-clamping means including means for moving the block along the frame for loosening or tightening the band ends.

10. In a matrix retainer, a frame, a matrix band end clamping block slidably carried by the frame, said frame having a head at one end with a central band-frame having a head at one end with a central band-receiving slot extending throughout the length of the head and two laterally-extending band-receiving slots communicating with the first slot and extending to opposite sides of the frame, the central slot being adapted to receive the band ends of a matrix forming band whether the band ends are fed in from either lateral slot or entirely received in the length of the central slot, and means carried by the clamping block for clamping the band end portions that extend beyond the inner end of the central slot, said block being movable for drawing in the band ends for tightening the matrix about a tooth, said band-clamping means including means for moving the block along the frame for loosening or tightening the band ends, both said band-clamping means and the block-moving means extending beyond the frame end disposed opposite to the head and projecting beyond the mouth so as to be independently operable from a point exterior the mouth.
